UNITED STATES PATENT OFFICE

WILLIAM J. MCCLURG, OF PITTSBURGH, PENNSYLVANIA

CARBURETED-WATER-GAS APPARATUS

Application filed October 25, 1924. Serial No. 745,736.

This invention relates to improvements in gas generators having among its objects the provision of a plurality of annular compartments leading to a common chamber and having a valved carbureter provided with a plurality of baffles, each communicating with one of the said annular compartments.

Another object of the invention is to provide in a gas generator means for independent air supply to the lower end of a plurality of annular compartments and means for supplying steam to a chamber common to the said compartments.

These and other objects will become more apparent from a consideration of the accompanying drawing in which like reference characters designate like parts and in which

Fig. 1 is a sectional elevation of the improved apparatus claimed herein; Fig. 2 is a top plan view of the same, the carbureting chamber being shown in section; Fig. 3 is a sectional plan view on a plane indicated by the line III—III, Fig. 1; Fig. 4 is a sectional plan view on a plane indicated by the line IV—IV, Fig. 1.

In the practice of the invention the water gas generating chamber is provided with a central hollow shaft 2 and the chamber and shaft are divided into a plurality of symmetrically arranged compartments designated respectively 1a, 1b, 1c, 1d, and 2a, 2b, 2c, 2d, by vertical walls. The partition walls in the chamber 1 do not extend to the top arch thus providing a common chamber A with which all of the compartments 1a, 1b, 1c, and 1d communicate. The several compartments in the chamber and shaft are connected at points below the grates 3 by a port 4, controlled by a valve 5 operated by means of a rod 6 extending out through the walls of the chamber 1. Above the chamber 1 and in vertical alinement with the central shaft is arranged a carbureting shaft 7 divided into two compartments or chambers by a diametrically arranged wall 8 in line vertically with, and forming an extension of, one of the partition walls in the central shaft. The lower end of one of the compartments in the carbureting shaft communicates with the common compartment A of the chamber 1

through a port 9, the passage of gases through said port being controlled by a valve 10. In order to insure the thorough mixing of gases admitted to the carbureting column with the vaporized oil, introduced into the stack 7 by the pipe 11, a plurality of horizontally arranged baffles 12 are arranged in the compartments of the stack, said compartments communicating one with the other through a port 13 in the partition wall 8.

A plurality of openings 14, are formed in the top of the chamber through which coal is fed to the several compartments 1a, 1b, 1c, and 1d, preferably by means of hopper and bell devices B arranged in feeding relation to said openings. These hopper and bell devices (only one of which is shown) may be of any suitable construction known in the art.

In order to supply air for purposes hereinafter described, to lower ends of the compartments 1a, 1b, 1c, and 1d, a bustle pipe 15 suitably connected to a source of supply of air under pressure, by a pipe 16, is connected by branches 17 provided with regulating valves to the several compartments at points below the grates. Provision is made for introducing air into the common chamber A by means of a branch pipe 18 extending from the supply pipe 16 to lower ends of one of the coal feeding hoppers.

In certain operations hereinafter described, it is desirable to introduce steam into the lower ends of the compartments, 1a, 1b, 1c and 1d, also into the common chamber A, and provision is made for utilizing the heat contained in the generated gases for the generation of steam for such purposes. As shown in Fig. 1, the lower portions of the compartment of the carbureting shaft through which the gases descend, is provided with a port 19 connected by a pipe 20 to the steam generator of any suitable construction, whereby heat may be extracted from the gases and utilized for the generation of steam. A suitable construction to that end consists of a shell having tube sheets so arranged as to form chambers at the ends of the shell. The chamber at one end is divided by a transverse wall into the compartments 21 and 22. The pipe 20 is con-

nected to one of these compartments from which the hot gases will flow through the tubes 23 communicating with such compartment to the chamber 24 and from the latter through tubes communicating with the compartment 22. Steam is conducted by a pipe 25 to an annular pipe 26 surrounding the chamber 1 and having valved branches 27 communicating with the lower ends of the compartments 1a and 1b. As shown in Fig 1, the pipe 26 is provided with a valved branch 28 extending into the air branch 18.

Gases flow from the compartment 22 of the steam generator by the pipe 29 having a regulating valve 30, and connected by a pipe 31 which projects down below the surface of a body of water in a wash box 32. Gas is freed of condensable elements in passing through the water, and is conducted by a pipe 33 to a point of use or storage. In some operations the air blast gases generated will contain such a small percentage of combustible constituents as to be unfit for storage purposes; in such cases, the valve 35 of the vertical pipe 34 is lifted so that the blast gases will escape to the air.

When blasting up to bring the fuel charges in the compartments of the water gas generator 1 to a state of incandescence, the valve 10 controlling the flow of gases from the common chamber to the carbureting column, the valve 20a in the pipe line 20, and the valve 30 in the pipe 29 are opened; except as herein-after described. The valves in one or more of the branches 17 connecting the bustle pipe to the lower ends of the compartments 1a, 1b, 1c and 1d are opened and the valves 5 closed. Air will now flow up through the charges in the compartments and the blast gases generated therein will pass into the common compartment A and flow thence through the port 9 up one and down the other side of the carbureting column 7, through the pipe 20, the tubes of the steam generator, from the latter, to and out through the stack 34. After the charges in one or more of the compartments of the gas generator have been blasted up as described, the air is cut off and steam is admitted to the lower ends of the compartments through the branch pipes 17 extending from the bustle pipe 26 connected as hereinbefore stated to the steam generator. The water gas generated by the flow of steam through the incandescent charges in the generator, will follow the course hereinbefore described, but in lieu of permitting the combustible gases thus generated, to escape through the stack, the lid thereof is closed and such water gases will flow through the pipe 31, through the hydraulic seal 32 to a point of use or storage. If desired, the gas may be enriched by injecting oil through the pipe 11 into the gases flowing through the carbureter 7.

It will be understood that if desired the air blasting of the charge in one or more of the

compartments may be effected while steam is being passed through other charges, which have been previously blasted. In such case, the lean gases produced in blasting will mingle with the richer gases flowing from the other charges, but the lowering of the average of such mixture can be compensated for by the injection of oil as hereinbefore described.

In lieu of the method described, steam, after blasting up, can be admitted to the common chamber A through the pipe 28 and the lower end of hopper B so that the valve 10, being closed, and the valve 5 at the lower end of the hollow shaft opened, the steam will flow downwardly through the chambers in 1a, 1b, 1c, and 1d, and up through the compartments 2a, 2b, 2c and 2d in the central shaft, and thence through the pipe 20, steam generator, pipes 29 and 31 to and through the hydraulic seal. In making this down run, the charges in one or more of the compartments 1a and 1b can be blasted up while gas is being generated in the other compartment, by closing the valve or valves 5 in the passage connecting the lower end of the compartment to be blasted and opening the valve in the branch pipe 17, connecting such compartment with the bustle pipe 15. The air blast gases generated in the blasting up will enter the common chamber A and pass down through the charges in the other compartments with the steam admitted to the common chamber through the branch pipe 28.

In order to remove water gas or carbon adhering to walls of the chambers or passages, and lodging behind projections or in corners, it is desirable from time to time to effect a return or scavenging run. In such cases, the valves 5 controlling communication between the lower ends of the compartments in the water gas generator and the central shaft are opened, and the valve 10 in port 9 and valves 30 and 20b in pipes 29 and 16 are closed. Steam is admitted into the chamber 22 in the steam generator through the pipe 36, and passes down through some of the tubes of the steam generator and up through others to chamber 21 and then along pipe 20 to and through the carbureting column and also the compartments 2a, 2b, 2c and 2d, in the central shaft. From the lower ends of the compartments the flow of steam and gases will be up through the charges in the compartments 1a, 1b, 1c and 1d to the common chamber A and from that chamber by a pipe 37 to the hydraulic seal. The valve 38 in the pipe will be closed except when making a return or scavenging run.

A desirable method of operation consists in closing the valves in branches 17 from the bustle pipe, the valves in branches 18 and 39 and valve 20a, and opening valve 20b and valves 5 at lower end of central shaft 2. Air will then flow through pipes 16 and 130

20 through carbureter 7 and down through the shaft up through the incandescent charges in the producer to the common chamber A, thence through the pipe 37 to the hydraulic seal 32, the valve 38 being open. 5 If desired, steam may be admitted below the incandescent charges during this run.

It should be stated that coal or other fuel is charged into the several compartments 1a, 10 1b, after the blasting up operations, and if necessary for combustion and for cooling valve 10, air is admitted into the common chamber during the up-blasting operations through the pipe 18 and pipe 39. When 15 making down runs it is preferred that the blasting up operations should be effected in succession in the several compartments 1a, 1b, as in this way, the hot gases formed in the blasting up can be utilized for further 20 gasifying the coal and vaporizing the tars, and other by-products distilled from the coal charged into the other or gas-generating compartments.

As the surfaces in the carbureter and passageways leading therefrom to the steam generator, may become heavily coated with carbon which can be removed only by combustion, provision is made for introducing air into the pipe 20 by means of a branch pipe 39 25 extending from the supply pipe 18, and provided with a valve 40, and from the pipe 20 extends an outlet pipe 41 having a controlling valve 42. During the scavenging run hereinbefore described, the valve 40 is open to 30 supply air for the combustion of carbon.

As the valve 10 in the passage connecting the common chamber A with the lower end of the stack is subjected to high temperatures, especially during the blasting-up operation, 40 provision is made for preventing excessive heating of the valve. A convenient construction to that end consists in providing a pocket 43 for the reception of the valve when raised and the air supply pipe 16 is connected by 45 a valved branch pipe 39 to such pocket.

I claim herein as my invention:

1. Carbureted water gas apparatus including a water gas generator having a plurality of compartments in angularly spaced relation, communicating at their upper ends with a common chamber, a superposed carbureter having a valved connection with the common chamber and provided with a plurality of baffles, means for independently supplying air to the lower ends of the compartments, and means for independently supplying steam to the several compartments. 50

2. Carbureted water gas apparatus including a water gas generator having a plurality of compartments in angularly spaced relation, communicating at their upper ends with a common chamber, a superposed carbureter having a valved connection with the common chamber and provided with a plurality of baffles, means for independently supplying 55

air to the lower ends of the compartments, means for independently supplying steam to the several compartments, and means for supplying air to the common chamber.

3. Carbureted water gas apparatus including a water gas generator having a centrally arranged hollow shaft, said shaft and the annular space around the shaft being divided into a plurality of vertical compartments, the annularly arranged compartments having valved connections with the lower ends of the compartments in the shaft, and communicating with a common chamber, a superposed carbureter provided with baffles and communicating with the compartments in the shaft and having a valved connection with the common chamber, means for supplying air independently to the lower ends of the annularly arranged compartments, and means for supplying steam to the common chamber. 70 75 80 85

4. Carbureted water gas apparatus including a water gas generator having a centrally arranged hollow shaft, said shaft and the annular space around the shaft being divided into a plurality of vertical compartments, the annularly arranged compartments having valved connection with the lower ends of the compartments in the shaft, and communicating with a common chamber, a superposed carbureter provided with baffles and communicating with the compartments in the shaft, means for supplying air independently to the lower ends of the annularly arranged compartments, and means for supplying steam to the common chamber, and means for feeding fuel to said compartments. 90 95 100

5. In a carbureted water gas apparatus, a water gas generator having a central hollow shaft extending from the bottom of the generator through the roof thereof, said shaft having diametric walls dividing its interior into a plurality of vertical passages or compartments, radial walls extending upwardly from the bottom of the generator and dividing the annular space between the walls of the generator and the central shaft into a plurality of open-topped compartments for the reception of fuel, valved passages connecting the lower ends of the fuel compartments and the passages in the shaft, and a valved gas passage connecting the portion of the generator above the fuel compartments with the upper portion of the shaft. 105 110 115

In testimony whereof, I have hereunto set my hand.

WILLIAM J. McCLURG.
